UNITED STATES PATENT OFFICE

2,578,060

EGG CASE

Jesse R. Grant, Chicago, Ill.

Application February 21, 1946, Serial No. 649,211

9 Claims. (Cl. 229—15)

1

This invention relates to a new and improved shipping case and method of making the same from fibreboard.

It is a main object of the invention to provide a method of making from fibreboard a shipping case particularly adapted for the shipment of eggs and similar fragile articles.

Another object of the invention is to provide a fibreboard egg case having standard dimensions.

Another object of the invention is to provide an egg case that is closed by a cover which is locked on the case at both ends and in the middle, and is capable of being completely removed from the case.

Still another object of the invention is to provide a new and improved cover for an egg case that fits entirely within the boundaries of the sides and ends of the case, and is free from overhanging or projecting portions.

Still another object of the invention is to provide a fibreboard egg case that has smooth, planar outer and inner side walls and ends.

Another object of the invention is to provide in a shipping case a central partition that is securely fastened to both side walls and to the bottom of the case.

Still another object of the invention is to provide a fibreboard shipping case that is strong and light and capable of being manufactured at low cost.

Further objects of the invention not specifically mentioned here will be apparent from the detailed description and drawings which follow, reference being had to the following drawings in which a preferred embodiment of the invention is shown by way of example, and in which:

Figure 1 is an isometric view of a preferred embodiment of the invention at one stage of its assembly;

Figure 2 is an isometric projection of a slightly modified form of the invention partially assembled;

Figure 3 is a cross-sectional view taken longitudinally through a case and showing still another form of the invention;

Figure 4 is a cross-sectional view taken longitudinally through the case and showing still another embodiment of the invention; and

Figure 5 is an exploded view in isometric projection of still another embodiment of the invention.

Standard egg cases, for example, heretofore mainly composed of wood, have certain definite outside dimensions, particularly length and

2

width, which must be maintained if the cases are to pack properly in freight cars and trucks. Recently fibreboard cases have been employed in lieu of wood as a war measure, these cases being composed either of so-called corrugated board or in some instances of solid fibreboard. Insofar as I am aware, none of these prior art fibreboard cases has maintained standard length and width coupled with standard egg space, with this space surrounded by smooth, flat wall surfaces capable of permitting proper insertion and removal of standard fillers and flats.

Corrugated fibreboard, in particular, is more resilient than wood and when properly constructed to standard dimension on the fibreboard case is capable of carrying eggs in shipment with less damage than is encountered in wooden cases. It is to this end that the present invention is directed.

20 In the preferred embodiment of the invention fibreboard cases composed of either corrugated or plain board are built to standard outside dimensions and are provided with full-size egg space surrounded by smooth planar walls. Adequate cushioning is provided in both ends of the case to take up end shocks encountered in shipping. The partition by which the case is divided into two egg spaces, is securely anchored to the bottom and both sides of the case, and is constructed 25 so as to provide adequate cushioning between the two sections of the case.

Formed in the end sections and partition of the case are grooves adapted to receive tongues on the cover of the case and disposed within these 30 grooves are locking elements adapted to engage co-operative elements in the tongues on the cover to lock the cover on the case at both ends and in the middle. This arrangement improves upon the standard wooden egg case whose cover 35 is fastened only at the ends. The cover of the instant invention is composed of fibreboard, either double-faced corrugated or plain, and is positioned on the top of the box with air spaces along the edges to permit proper ventilation of the contents.

The cover does not overhang the case on the sides and can be removed from the end of the case to permit necessary inspection of the case, even though it be in position in a car with other 40 cases firmly abutting against it on either side.

Referring now to the drawings in more detail, particularly Figure 1, wherein there is shown a case capable of being formed from a single sheet of stock, which sheet is cut and scored to form 45 a bottom section 1 and side sections 2 and 3. Ex-

tending from the bottom section 1 of the blank are members 4 and 5 which form part of the end of the case. Extending from the ends of side section 2 are extensions 6 and 7 and from the side sections 3 are extensions 8 and 9 which extensions also enter into the ends of the case, as will presently appear.

Disposed on the bottom section 1 is a liner indicated generally at 10, and consisting of an end section 11 and bottom section 12 and tongue 13, which may be formed by folding the liner back upon itself to place two thicknesses of material in the tongue, another bottom section 14, and another end section 15. If desired, the liner may be made from two pieces of material, each folded to generally U-shape and these pieces secured together to place two thicknesses of material in tongue 13.

Stapled to the side member 2 is a partition element 16 and stapled to the side section 3 is a partition element 17. Partition element 16 has side members 18 and 19, which are of such height as to extend to the top edge of the side and of such width that they will extend to the longitudinal median line of the case. Partition member 16 has similar sections 20 and 21 which are of identical dimension.

In assembling the case, liner 10 is placed upon the bottom section 1 and one of the sides, 2 for example, is folded along its score line 22 into position at right angles to the bottom section 1. Sections 18 and 19 of partition member 16 are folded onto opposite faces of the tongue 13 on the partition and secured thereto in any preferred manner, such as by stapling. Ends 6 and 7 on side 2 are folded on their respective score lines into position alongside of and outside of end sections 11 and 15 respectively of the liner.

Side section 3 of the case is next folded along its score line 23 into vertical position and sections 20 and 21 of the partition means 17 are folded alongside opposite faces of the tongue 13 and into abutment with sections 18 and 19 respectively. Sections 20 and 21 are secured to the tongue in any preferred manner, as by stapling. End sections 8 and 9 of the side 3 are then folded along their respective score lines 24 and 25 into position outside of and adjacent to sections 6 and 7 respectively.

End section 4 of the bottom 1 is next folded along score line 26 outside of end section 8 and then bent along score line 27 over the top of sections 6 and 8 and bent again along score line 28 downwardly on the inside of sections 6 and 8 into abutment with the upper edge of section 11 of the liner. Sections 11, 6, 8 and 4 are then secured together by suitable means, such as staples, to complete the one end of the case.

In a similar manner after sections 7 and 9 have been folded alongside of each other, bottom section 5 is folded along score line 30 up over the outside of these sections and then folded along score line 31 across the top thereof, and again folded along score line 32 down on the inside of section 7 to bring the inmost portion 33 of the extension into abutment with the top edge of liner section 15. The end is then secured together by suitable means, such as staples.

It will be noted that section 6 and 8 are cut away as indicated at 35 and 36 respectively, so that when folded together between the liner and outer element in the end of the case, a groove will be formed. The portion of the end section 4 between score lines 27 and 28 contain gener-

ally rectangular perforations 37 and 38, which register with the groove so formed. Similar grooves 40 and 41 in members 7 and 9 respectively form a groove with which perforations 42 and 43 in the portion of end section 5 between score lines 31 and 32 are registered. The upper edge of tongue 13 is cut away as indicated at 45 to form a groove between partition members 18, 19, 20 and 21 and generally T-shaped tongues 46 and 47 are disposed within this groove, for a purpose which will presently appear.

The cover 50 may consist of a single piece of stock folded back upon itself to form a central tongue 51 having two thicknesses of material and folded back upon itself to form an end tongue 52 and a second end tongue 53, both of which are composed of two thicknesses of material. Obviously, if desired, the cover may be made of two pieces of material joined together in tongue 51 by suitable means, such as staples, in lieu of the single piece construction shown.

Formed in the tongue 51 are locking means including shoulders 54, which are adapted to be registered with and engage complementary shoulders on tongues 46 and 47. Tongue 52 contains similar locking means having shoulders 55, which locking means register with the rectangular perforations 37 and 38 in the one end of the case to secure the cover thereto. It will be noted that shoulders 54 are spaced farther from the underside of the cover than are shoulders 55, so as to register properly with the locking means in the case. Tongue 53 is provided with similar locking means having shoulders 56 which locking means registers with the perforations 42 and 43 in that end of the case.

To position and lock the cover on the case the cover is first moved downwardly to register the tongues with their respective slots and then moved laterally to engage the locking shoulders.

The case thus formed contains four thicknesses of material in each end and four thicknesses of material in the partition. It has a double bottom and single thickness side walls. The egg receiving cavities within the case are of full size, and are surrounded by smooth planar walls which facilitate easy insertion and removing of the packing elements with which the case is filled. The cover which also consists of a single thickness of material is securely held on the case at both ends and in the middle, and since the partition is securely fastened to both sides of the case, and if desired may also be fastened to the bottom by fastening the liner sections thereto in suitable manner, such as by stapling, the resulting structure is exceedingly strong and particularly adapted to resist endwise shocks placed upon it. The outer surfaces of the case are all smooth planar surfaces, thereby permitting the case to be stacked adjacent to other cases in a tight pile, better enabling the case to withstand shocks placed upon it in shipment.

The case shown in Figure 1 may be provided with handholes in the end, as hereinafter explained, these holes being omitted from the drawing to avoid an unnecessary complication thereof.

Figure 2 shows a case constructed in the same general manner as Figure 1 except that the end sections 60 and 61 of the liner are carried up to the top edge of the case and the end extensions 62 and 63 of the bottom sections are terminated flush with the top edge of the sides. Grooves 64 are formed in the end walls of the case as before and tongues 65 projected into those grooves as before.

The partition shown in Figure 2 employs a slightly different construction than that shown in Figure 1. Tongue 66 of the liner is employed as before and one partition member 67 is equipped with a footlike projection 68 that is secured to one side wall 69 of the case by suitable means, such as staples. This partition member extends from the liner to the top of the case and is wide enough to extend across the case into abutment with the other side wall 70 thereof. A second partition member 71 is disposed on the other side of the tongue 66 and provided with a foot 72 that is secured to the side wall 70 in any preferred manner, such as by staples, the partition member 71 also extending from the liner to the top edge of the case and across the case into abutment with the side wall 69. The tongue 66 and partition members 67 and 71 are secured together in any suitable manner, such as by staples. Tongue 66 is equipped with locking means 73 that project into the groove 74 formed between the partition means 67 and 71 at the top edge of the case.

The cover shown in Figure 2 is similar to that shown in Figure 1, having single thickness main members 75 with a double thickness tongue 76 located at the center of the cover and end tongues 77 and 78 located at the ends thereof. Locking means 79 are formed in each of the tongues 76, 77 and 78, and adapted to be registered in the grooves and with the locking shoulders on means 65 and 73 disposed in those grooves.

The covers shown in both Figures 1 and 2 are somewhat narrower than the case to provide for top ventilation of the case and are inserted and locked on the case first by a vertical movement and then by a horizontal movement laterally of the case. In certain instances it may be desirable to double-lock the cover, and the construction shown in Figure 2 lends itself particularly well to this feature.

Projecting upwardly from the one side wall 70 is a flange 80 joined to the side wall along a score line 81. The ends of the flange 80 extend beyond the end walls of the case and are scored so that they may be folded back upon themselves to form double thickness tabs 82 which project at right angles to the flange 80 and are adapted to fit into the grooves 64 in the ends of the case. After the cover has been moved laterally to lock it on the case, flange 80 is bent along score line 81 and tabs 82 stuffed down into the groove alongside of the tongues on the cover therein to prevent lateral movement of the cover. The flange 80 is then disposed in abutment with the edges of the cover. A flange similar to 80 will be provided also on the side wall 69 of the case, but this flange has been omitted from the drawing to prevent an unnecessary complication thereof.

The case shown in Figure 2 contains four thicknesses of material in each end, four thicknesses in the partition, two thicknesses of material in the bottom and a single thickness of material in each side and in the cover. The egg receiving spaces in the case are full-size and bounded by smooth planar walls and the outside surfaces of the case are all smooth planar surfaces, free from obstructions or projections. Handholes such as indicated at 83 may be provided in each end of the case, if desired. The case shown in Figure 2 is formed from a single sheet of material by folding in the manner more fully described in connection with Figure 1. The liner may be formed from a single piece of material suitably bent to form a double thickness center tongue, or may be formed from two pieces of material joined to-

gether in the tongue by suitable means, such as staples.

In certain instances it may be desirable to form a case having but a single thickness of material in the bottom. The embodiment of the invention shown in Figure 3 is a cross sectional view down through the longitudinal median line of such a case. In this figure the bottom section of the case 90 has end extensions 91 and 92 folded upwardly to form the outer surfaces of the ends of the case. The one side 93 of the case has projections 94 and 95 which are folded to form one member in the end wall of the case. The other side wall, not shown in Figure 3, has similar end projections 96 and 97 folded to form an additional thickness of material in the end walls of the case. Extra pieces 98 and 99 are built into the end walls of the case and extended to the top edge thereof.

The sections 94 and 96 of the one end of the case are cut away as shown in Figure 2 to form a groove disposed between the top edges of members 91 and 97, and locking means such as 65 are projected into this groove. End wall sections 95 and 98 are similarly cut away to form a groove in the other end of the case and similar locking means, not shown, are projected into this groove.

The partition is formed of a central tongue 98 having feet 99 disposed against the bottom and projecting outwardly on opposite sides of the tongue 98. These feet are secured to the bottom 90 of the case by suitable means such as staples. Locking means similar to means 73 in Figure 2 are formed in the top edge of the tongue 98. Partition members 100 each of which may be of the type shown in Figure 2 or the type shown in Figure 1, are disposed on opposite faces of the tongue and secured thereto by suitable means such as staples.

The cover 101 is of construction identical of 40 that shown in Figure 2, having a central tongue 102 and end tongues 103 which are registered with the grooves in the case to position and lock the cover thereon. Secondary locking means, such as 80 of Figure 2, may be employed in this embodiment of the invention, if desired.

As will be seen in Figure 3, each of the four thicknesses of material in the end wall of the case can be perforated as shown at 108 to form a handhold. The material thus cut from the case 50 in the outer thickness of the wall being left attached at the upper edge of the perforation as shown at 104. The perforation in the third thickness of the material, 95 for example, is wider than the perforation in the other thicknesses to 55 form a slot 105, thereby permitting the tab 106 left in the outer thickness of material 92 to be folded along suitable score lines into the groove 105. The tab may be secured therein by suitable means, such as staples, and forms a smooth upper 60 edge in the handhold, permitting a workman to pick up the case without damaging the material in the end walls. The perforations forming the handhold extends into the egg space in the case, thereby aiding to provide ventilation in those 65 spaces. This type of handhold may be used in the embodiments of the invention shown in both Figures 1 and 2.

In certain instances it may be advantageous to 70 form the case as a box complete in itself, and to form the partition and locking means as a liner unit adapted to be fit into the box. Figure 4 shows such an embodiment of the invention. The case consists of a single thickness bottom 110, an end section having three thicknesses of material 75 111, formed by folding together extensions of the

sides and bottom as hereinbefore explained. The liner 112 has a central tongue 113 consisting of two thicknesses of material and end tongues 114, each consisting of two thicknesses of material. The top edges of the tongue and end members 113 and 114 are cut away to form a groove and locking means as in the embodiment shown in Figure 2. Auxiliary planar members 115 are disposed against the inner faces of the tongues 114 to complete the grooves.

The three thicknesses of material 111 forming the end walls of the case may be suitably secured together and the three thicknesses of material forming the ends of the liner may be similarly secured together as by staples, and the liner fitted into the case. Partition means 116, preferably of the type shown in Figure 2, are fastened to the side walls of the case and disposed alongside of the tongue 113, and secured thereto—preferably by staples—to lock the partition in the case. The cover used in this embodiment of the invention is the same as that shown in Figure 2 and need not be explained again in detail. The embodiment of the invention shown in Figure 3 permits use of a thinner stock in the case, and is, therefore, adapted particularly to cases composed of so-called fibreboard rather than corrugated board. Standard dimensions are maintained by this arrangement. The case has six thicknesses of material in each end, four thicknesses in the partition, two thicknesses in the bottom and a single thickness in each side and in the cover. Hand-holds such as shown in Figure 3 may be employed in the end walls of this embodiment of the invention, if desired. The outer surfaces of the case are all smooth planar surfaces as before.

The embodiments of the invention shown in Figures 1 to 4 inclusive are all designed to be made from a single sheet of stock in the main outer case. In order to provide for better ventilation in the case the side walls may contain perforations, not shown, to permit entrance of air at or near the bottom of the case. In certain instances, particularly where the cases are to be used in storage, it may be advantageous to make the case out of several individual pieces of material joined together in such a manner as to leave a crack along the bottom edge of the case as is the case in wooden construction, so as to better permit free circulation of air through the case. In Figure 5 I have shown such a construction wherein the case consists of side sections 120 and 121, each of which is U-shaped and has end forming projections 122 and 123, respectively. The upper edges of these sections are cut away to form grooves and locking means 124, as before. The bottom forming section 125 has end members 126, adapted to fit up along the outside of the ends 122 and 123. A liner such as the liner shown in Figure 2 fits within the case and has end sections disposed against the inner one of the sections 122 and 123 to place four thicknesses of material in the end walls of the case.

Each of the side members 120 and 121 is equipped with a partition forming means 127 shown as the type shown in Figure 2, although the type shown in Figure 1 may equally well be used. In Figure 5 only one such means 127 is shown to avoid unnecessary complication of the drawing. With the partition in place and secured together, the case so formed has four thicknesses of material in each end wall, two thicknesses in the bottom with an air space between the side walls and bottom, and a single thickness of material in each side wall. The partition contains four thicknesses of material and is securely

fastened to both sides of the case and to the bottom. The cover shown in Figure 2 may be employed in this embodiment of the invention and if desired, flanges such as flange 80, Figure 2, may be placed on the upper edges of the side walls to permit double locking the cover on the case.

While I have illustrated a locking means as comprising generally T-shaped members disposed in the grooves in the ends and partition of the case, I have done so by way of example only, as other types of locking means may equally well be used within the teachings of the invention. With the form of locking means shown, the cover will lock properly on the case when turned end for end, and may be removed from the case, even when the case is stacked tightly and is surrounded by cases on both sides and both ends. This feature is important, as it permits opening the case to inspect for damage in shipment before the case is removed from the car.

Throughout the specification I have referred to the case as one for containing eggs. Obviously, the teachings of the invention may be equally well applied to other uses than for egg cases, and I am not to be limited by the particular embodiment shown by way of example.

Shipping cases built in accordance with the teachings of my invention have many advantages. Standard dimensions of standard wood cases which they supplant can be maintained, the resulting case being lighter than a wooden case and surprisingly strong. Both ends are flat planar surfaces so that impacts placed on the case are transmitted equally to the side walls, bottom and cover of the case, which has been impossible in wooden cases, because of the outside cleats that they have contained. Produce receiving spaces in the case may be made full-sized and bounded by smooth planar walls, while keeping the outside dimensions of the case standard. The cover being locked to the case at both ends and in the middle aids the side walls and bottom in resisting end applied shocks with the result that there is less damage to the contents than in cases of this kind heretofore. The end walls and partition being composed of material having a certain amount of inherent resiliency absorbs shocks better than wooden cases. Since the partitions are securely fastened, the produce in each individual pocket in the case and the packing material in which it is placed, takes care of its own endwise shocks, and these shocks are not cumulative as in cases where a free or a so-called floating partition is used.

While I have chosen to show my invention by illustrating and describing a preferred embodiment of it, I have done so by way of example only, as there are many modifications and adaptations which can be made by one skilled in the art within the teachings of the invention.

Having thus complied with the statutes and shown and described a preferred embodiment of my invention, what I consider new and desire to have protected by Letters Patent, is pointed out in the appended claims.

What is claimed is:

1. The combination in a fibreboard shipping case for eggs of a bottom composed of two thicknesses of material, sides composed of one thickness of material, ends composed of four thicknesses of material and a partition composed of four thicknesses of material and fastened to said sides and bottom, and a cover composed of one thickness of material and having projections adapted to register with said ends and partition,

and laterally extending bosses within said ends and partition and engaging ears on said projections for locking said cover to said ends and partition to close the case.

2. The combination in a fibreboard shipping case for eggs of a bottom composed of two thicknesses of material, sides composed of one thickness of material, ends composed of four thicknesses of material, and a partition composed of four thicknesses of material and fastened to said sides and bottom of the case, the two center ones of the four thicknesses of material in the partition and ends of the case being cut away to form slots opening into the edge of said elements, and a cover composed of one thickness of material and having center and end projections that contain two thicknesses of material which projections are adapted to fit into said slots to position the cover on the case and laterally extending bosses within said slots and engaging ears on said projections to lock the cover to the ends and partition of the case.

3. A shipping case comprising a bottom section and two side sections, an extension on each end of each of said side sections which extensions are cut away along the top of the section to make the extension lower than the section, locking means projecting from the tops of said extensions and terminating below the tops of said sections, the extensions on one side overlapping the corresponding extensions on the other side at the ends of the case, an extension on each end of the bottom section disposed outside of the overlapping side section extensions and extending to the top edges of the side sections, a liner having end members disposed inside of said overlapped side section extensions and extending to the tops of the side sections, said liner members and bottom section extensions together forming grooves in the ends of the case into which grooves said locking means extend, bottom sections of said liner disposed on the bottom of the case, a tongue section of said liner extending upwardly from the bottom sections of the liner and terminating in locking means disposed below the top edges of said side sections, partition means secured to said side sections and overlapping said tongue to form a partition in the case, said partition means extending to the top edges of the side sections and forming a groove in said partition, means securing together the end sections of the case, and means securing together said partition means and tongue.

4. A shipping case comprising a bottom section and two side sections, an extension on each end of each of said side sections which extensions are cut away along the top of the section to make the extension lower than the section, locking means projecting from the tops of said extensions and terminating below the tops of said sections, the extensions on one side overlapping the corresponding extensions on the other side at the ends of the case, an extension on each end of the bottom section disposed outside of the overlapping side section extensions and extending to the top edges of the side sections, a liner having end members disposed inside of said overlapped side section extensions and extending to the tops of the side sections, said liner members and bottom section extensions together forming grooves in the ends of the case into which grooves said locking means extend, bottom sections of said liner disposed on the bottom of the case, a tongue section of said liner extending upwardly from the bottom sec-

tions of the liner and terminating in locking means disposed below the top edges of said side sections, partition means secured to said side sections and overlapping said tongue to form a partition in the case, said partition means extending to the top edges of the side sections and forming a groove in said partition, means securing together the end sections of the case, a cover for said case, and means on said cover adapted to extend into said grooves and to engage the locking means therein to secure the cover on the case.

5. A shipping case for eggs comprising, bottom, side and end sections formed from a single piece of fibreboard, said end sections each consisting of three thicknesses of said material, a liner for said case consisting of end, bottom and center sections and having one thickness of material in the end and bottom sections, and two thicknesses of material in the center section, means for securing said central section of the liner to the sides of the case, said means and central section together forming a partition in the case containing four thicknesses of material, the two center ones of the four thicknesses of material in said end and center sections being shorter than the other thicknesses therein to form grooves in said sections and cover locking means disposed in said grooves and adapted to be engaged by a cover for the case and to lock the same on the case.

6. A shipping case for eggs comprising, bottom, side and end sections formed from a single piece of fibreboard, said end sections each consisting of three thicknesses of said material, a liner for said case consisting of end, bottom and center sections and having one thickness of material in the end and bottom sections, and two thicknesses of material in the center section, means for securing said central section of the liner to the sides of the case, said means and central section together forming a partition in the case containing four thicknesses of material, the two center ones of the four thicknesses of material in said end and center sections being shorter than the other thicknesses therein to form grooves in said sections, a cover, tongues depending from said cover and adapted to be fit into said grooves to position the cover on the case, and means in said tongues for engaging said locking means to lock the cover on the case.

7. A shipping case comprising, bottom, side and end sections formed from a single piece of fibreboard, said end sections each consisting of three thicknesses of said material, a liner for said case consisting of end, bottom and center sections and having one thickness of material in the end and bottom sections, and two thicknesses of material in the center section, means for securing said central section of the liner to the sides of the case, said means and central section together forming a partition in the case containing four thicknesses of material, the two center ones of the four thicknesses of material in said end and center sections being shorter than the other thicknesses therein to form grooves in said sections, a cover, tongues depending from said cover and adapted to be fit into said grooves to position the cover on the case, flanges on the side sections of said case, adapted to be folded over into abutment with the cover when the cover is locked on the case, and tabs on said flanges adapted to be inserted into said grooves to double lock the cover on the case.

8. A shipping case for eggs composed of fibreboard and comprising bottom, side and end sections formed of a single piece of fibreboard, said end sections consisting of three thicknesses of said material, a liner for said case composed of a single piece of fibreboard folded back upon itself to form a tongue containing two thicknesses of material and folded to form single thickness bottom and end sections on either side of said tongue, said tongue being disposed centrally in said case and extending between the sides thereof, means including a thickness of fibreboard stapled to each side member of the case and folded alongside of said tongue on each side thereof and stapled to the tongue for fastening the tongue to the sides of the case, said tongue and fastening means together forming a central partition in said case containing four thicknesses of material, and means including staples for securing the end sections of said liner to the end sections of the case, to place four thicknesses of material in the ends of the case.

9. A shipping case for eggs composed of fibreboard and comprising bottom, side and end sections formed of a single piece of fibreboard, said end sections consisting of three thicknesses of said material, a liner for said case composed of a single piece of fibreboard folded back upon itself to form a tongue containing two thicknesses of material and folded to form single thickness bottom and end sections on either side of said tongue, said tongue being disposed cen-

trally in said case and extending between the sides thereof, means including a thickness of fibreboard stapled to each side member of the case and folded alongside of said tongue on each side thereof and stapled to the tongue for fastening the tongue to the sides of the case, said tongue and fastening means together forming a central partition in said case containing four thicknesses of material, a cover for said case composed of a single piece of fibreboard folded to form a central and end tongues adapted to register with the partition and end sections of the case respectively, and means on said cover tongues co-operating with means in said partition and end sections for locking said cover to the partition and end sections of said case.
